(57) **CLAIM**

The ornamental design for a crucial ligament surgical drape, as shown and described.

DESCRIPTION

FIG. 1 is a perspective view of a crucial ligament surgical drape showing my new design on a wearer's leg; FIG. 2 is a perspective view thereof in partially collapsed position;

FIG. 3 is a front elevational view thereof;

FIG. 4 is a rear elevational view thereof;

FIG. 5 is a right edge view thereof;

FIG. 6 is a left edge view thereof;

FIG. 7 is a top plan view thereof; and,

FIG. 8 is a bottom plan view thereof.

The portions shown in broken lines in FIGS. 1, 2 and 3 are for information only and form no part of the instant design.
